CHARLES R. GABRIEL, OF NEW YORK, N. Y., ASSIGNOR TO E. W. BLISS COMPANY, OF BROOKLYN, NEW YORK, A CORPORATION OF WEST VIRGINIA.

FEED-CONTROLLING MECHANISM FOR PUNCHING-PRESSES.

1,099,545.

Specification of Letters Patent.

Patented June 9, 1914

Application filed February 6, 1912. Serial No. 675,733.

To all whom it may concern:

Be it known that I, CHARLES R. GABRIEL, a citizen of the United States, residing in the borough of Brooklyn, county of Kings, 5 city and State of New York, have invented certain new and useful Improvements in Feed-Controlling Mechanism for Punching-PresSES, of which the following is a specification.

10 This invention relates to apparatus for facilitating the feeding to a punching press or analogous machine, of a sheet of metal, cardboard, etc., which is to be punched or otherwise treated by such machine.

15 In punching a series of objects, such, for example, as can heads, from a sheet, it is customary to present one side or end of the sheet to the punch, and, starting at one corner, to feed the sheet laterally so as to punch

20 out one lateral row of punchings; in the case of round punchings or other shapes which may similarly interfit, it is customary to alternate the punchings of the second row with those of the first row, so that the

25 punchings enter partly between the previous punchings so as to economize material. This method of alternate punching is known as a stagger feed. Thus the sheet is fed in alternate lateral directions, being advanced

30 at the end of each row of punchings to bring it into position for the next row, and being displaced half the length of the lateral feed in starting each row so as to properly alternate the punchings. It is customary

35 also to provide the press with means for cutting away the scrap or skeletonized plate which is left after each row of punchings in order to make room for the next forward feed of the sheet. For thus feeding a sheet

40 to the punching press two means are commonly provided, either (1) a gage for indicating the proper spacing of the feeding movements, the entire feeding operation being performed by hand aided or guided by

45 such gage; or (2) a purely mechanical feeding mechanism whereby when the operator places a sheet in position upon a feeding table and starts the machine, the necessary feeding movements are executed automatically. The latter means involves a

50 more or less complicated mechanism accompanied by the disadvantages of high first cost, liability to get out of order, and difficulty of adjustment when it is desired to use a different size of sheet or to make

punchings requiring a different length of feed. Such automatic feed mechanism is chiefly available where great numbers of like punchings are to be made so that the machine rarely requires adjustment. 60

The present invention aims to provide a very simple and easily operated mechanism for insuring the correct and accurate feeding of a sheet by hand, so that such hand feeding may have practically the same precision and accuracy as if an automatic feeding mechanism were employed, while requiring a minimum of skill in manipulation. 65

A further object is to facilitate the adjustment of the feed-controlling means for punchings of different size, or requiring different spacing, and for sheets of different sizes. 70

To these ends my invention provides a 75 punching press of any ordinary construction having a suitably extended bed or stationary table, with a laterally movable feed table, having means for engaging the sheet from which the punchings are to be made, 80 these means being adjustable to accommodate sheets of different lateral dimensions. The feed table is guided so that it can move from right to left and left to right in an invariable path; and it is so moved 85 manually by the operator, guided by a series of stops comprising a rack bar carried by the feed table, and a movable stop or abutment seated on the fixed bed of the press and automatically withdrawn after each 90 punching operation in order to permit of the manual feeding movement, being replaced in time to locate the feed table at the end of such movement. The teeth of the rack bar and the tooth or teeth of the movable stop are so proportioned and related that when the direction of feed is changed the first feeding movement is made of half the scope of the normal feeding movements, whereby to correctly provide the requisite 95 staggered feed. The feed table carries clamping means for holding fast the sheet during the punching of a row of perforations, and releasing means is provided, under the control of the operator, for opening 100 the clamps to release the sheet after the punching of each row, in order that the operator may move the sheet forward into position for punching the next row. The feed table is provided with a handle or bar 105

110

extending parallel with its path of movement and which is grasped by the operator to manually feed the table; and the same bar is utilized to operate the clamping means, this being done by a twisting or oscillatory movement of the bar. Gages are provided for initially locating the sheet for punching the first row and for subsequently limiting the forward feed of the sheet before the 10 punching of each subsequent row.

The accompanying drawings illustrate the preferred embodiment of my invention as applied to an ordinary tip-back punching press of the well-known Bliss type.

15 Figure 1 is a side elevation of the upper or tilting member of such press, this for convenience being shown in its upright position so that its bed or table is horizontal, although, as is well understood, such presses 20 are commonly operated in a back-tilted position so that the fixed table or bed is slanted backward, so that the sheet, on being advanced from row to row, moves obliquely downward. Fig. 2 is a plan of the 25 bed of the press showing the feed-controlling mechanism and gages, a fragment of the upright frame of the press being shown in horizontal section. Fig. 2^a is a sectional detail of an end of the handle H. Fig. 3 is a 30 front elevation of the stationary feed table and its accessories. Fig. 4 is an elevation of the right hand end or side of the parts shown in Fig. 2. Fig. 5 is a vertical section on the plane of lines 5—5 in Figs. 2 and 3. Fig. 5^a is a fragmentary section in a 35 different plane from Fig. 5, namely, the plane of the line 5^a in Fig. 3, the table being shown tilted. Fig. 6 is a fragmentary plan of a partly punched sheet. Fig. 7 is a 40 fragmentary front view of the feed stop. Fig. 8 is a fragmentary vertical section showing the details of the gage-operating handle.

Referring to the drawings, A designates the tilting frame of the press, and B its 45 bed or stationary table. The fixed bed or foot supporting the frame A is not shown, being well understood.

C is the feed table which moves from side to side over the table B. To facilitate this 50 movement it is mounted on rollers a a (Fig. 5) which roll upon the stationary bed, and rollers a' a' (Fig. 5^a) which roll against a rib B' on the bed, and as this is inclined backward, the weight of the table C keeps 55 it pressed back with these rollers bearing on the rib. The feed table C is thus suitably guided to insure its movement in a fixed rectilinear path.

D is the die, mounted as shown upon the 60 bed or table B.

E, Fig. 1, is the punch which enters the die. On each side and back of the die are scrap-cutters, each consisting of a rectangular die F' entered by a similar shaped 65 punch F, which together form a shear for

cutting the scrap that is left by the punching operations. These parts, being well understood, are not shown in detail.

The feed table C, while it might be a simple flat plate, is preferably made as an 70 open frame comprising longitudinal members b and c and end members d d. Upon the member b is fastened a metal plate e which supports the sheet to be punched. To the end members d d are fastened adjustable end frames f f which are set at such distance apart as to admit the sheet to be punched freely but snugly between them. To accommodate sheets of different dimensions these end frames f are made adjustable by means of set screws f' passing through slots and engaging one or another of a series of holes d' d' in the members d. The end members d are thus made wide enough to accommodate the maximum adjustment that is desired. 75 80 85 90

For clamping the sheet to be punched to the feed table C the latter is provided with clamping means consisting preferably of two levers G G, one at each end, pivoted or fulcrumed at g to the end frames f respectively. These are best shown in Fig. 5. The short arms to the rear of the fulcrum pins g are adapted to pinch the sheet against a plate e (or preferably against a 95 short piece of anvil plate e' in the same plane which is carried by the rear end of each of the frames f). The lever may thus clamp the sheet frictionally, but preferably each lever is armed with a pointed screw 100 or spur h which enters a small hole in the anvil plate and thus indents the sheet so as to prevent any risk of it slipping. To clamp the sheet with the requisite force each lever G is provided with a spring located 105 at i so as to engage and press up the long arm of the lever. This spring may be variously constructed; the construction preferred is that shown in Fig. 5, where the spring i is housed in a socket in the frame f 110 and presses up a plunger i' against a pin i² projecting from the lever. It is necessary to be able to open both clamps simultaneously by a single movement, and for this purpose the feed table is provided with 115 a handle-bar H which may be of simple cylindrical form and mounted to oscillate on an axis carried by supporting brackets j j at opposite ends, this handle being so connected to the levers G G that by turning it 120 in one direction it will depress the levers and open the clamps, whereas by turning it in the contrary direction it will release the levers and permit their springs to close the clamps. The construction shown in Fig. 5 125 is suitable, the handle H being pivoted eccentrically to the supporting brackets j j so that as it is turned it acts to depress or release the free ends of the levers G G. The handle may conveniently be constructed 130

of a tube fastened on a block j^3 at each end (Fig. 2^a) having an eccentric pivot pin j^4 passing freely through a hole in the bracket j . To limit the oscillatory movements of the handle the bracket carries a fixed pin j' which enters an arc-shaped slot j^2 in the end block. The handle H extends endwise of the feed table over its front portion, where it serves conveniently as the means by which the operator performs the feeding movements of the table. The handle or bar H thus serves a double purpose; namely, when moved to the left or right to feed the table, and when turned to release the clamps G G.

To the front of the feed table C is fastened a rack bar J which extends nearly from end to end of the feed table and has teeth projecting from it, these teeth being spaced apart between centers a distance equal to the space or feed between two successive punchings in the same row. The teeth are engaged by a movable stop or abutment K. This abutment occupies an invariable vertical plane, being however movable in this plane sufficiently to bring its stop tooth or shoulder into and out of the path of the rack bar teeth. Thus when drawn down, as shown in Fig. 3, the feed table may be freely moved, the teeth of the rack bar not encountering the stop K; when the stop is raised to the position shown in Fig. 7, the latter is in position to encounter and check the movement of the rack bar teeth. The movements of the stop K are performed automatically and by connection with the punching press, so that after each punching stroke and when the punch is lifted above the die, the stop is withdrawn, so as to free the rack bar and permit the operator to move the feed table to right or left preparatory to the next punching. These movements are performed by means of a cam L fixed on the crank shaft M of the punching press, which cam acts upon a roller l carried by a rod m, which through an elbow lever m', rod n, arm o, rock shaft p and arm p', communicates movement to a slide K' on which the stop K is mounted. The stop K is thus displaced downwardly for a time sufficient only to enable the operator to move the feed table enough to carry its rack teeth past the stop tooth k of the stop K; and after a sufficient interval to allow of this the stop K is restored to its original position, whereupon the operator, continuing the feeding movement, brings the next rack tooth to a firm seat against the stop tooth k and holds it there during the next punching operation. The engagement of the rack teeth with the stop teeth is clearly shown in Fig. 7. The stop K may have one tooth k or more, two being preferable as shown.

65 The spacing between the rack bar teeth

(being the dimensions x in Fig. 7), equals the length of a feeding movement. To commence the stagger feed requires a half feeding movement which is provided for by making the thickness or width of the rack bar teeth and stop teeth k such that the space x' between them is equal to half the dimension x ; hence, when the series of feeding movements in one direction is terminated, and after the operator has advanced the sheet forward (as will be described), when he begins to perform the feeding movements in the opposite lateral direction, the first feeding movement is of the distance x' , thereby gaging the feed table properly for the first punching in the next succeeding row, whereby the requisite stagger feed is secured. This half feed is thus accomplished automatically upon commencing each new row of punchings and by extremely simple gaging means.

The rack bar J is removably attached to the feed table in order that, when it is required to replace the die or punch by one making a smaller or larger punching, which requires a different amplitude of feeding, the rack bar may be removed and replaced by another rack bar having its teeth spaced apart the correct distance for this new series of punchings. Ordinarily only a limited number of different sizes of punchings are to be made by the same press for any given class of work, and for this it is easy to provide a corresponding series of rack bars. The stop teeth k also require to be replaced by others in case two or more of these teeth are employed, and for this purpose the stop K is made detachable from its slide K', being fastened thereto by any suitable means. It is preferable also that the rack bar J be made laterally adjustable with respect to the feed table C. For this purpose a suitable construction is that shown, wherein the rack bar is fastened by a succession of clamping screws q, q, Fig. 5, the nuts of which are preferably square blocks, seating closely in an undercut groove r formed longitudinally in the front face of the front member c of the feed table. Upon the loosening of these screws the rack bar may be removed endwise. Or by loosening the screws it may be adjusted endwise to bring it to the precise adjustment required for the initial feed, whereupon the clamping screws are all set tight to hold it firmly in position.

It is preferable to provide the feed table with end stops N N, these being fastened to it just beyond the ends of the rack bar J and preferably by similar clamping screws q, the nuts of which engage the same undercut groove r. These stops are so located that when the feed table has been moved to the position for the last punching of the row the stop at that end will abut against the side of the movable stop K and thereby pre-

vent any further movement in that direction. The stop shoulders on the stops N project sufficiently to continue in engagement with the stop K after the latter is displaced.

5 I will now describe gaging means for initially locating the advancing edge of the sheet and for determining its forward feed after the punching of each row.

10 At the back of the fixed bed or table B is mounted, near each side or lateral end, a saddle-piece P; supported by these two saddle-pieces is a gage-bar Q extending from right to left parallel with the path of movement of the feed table C. This gage-bar Q has a front face or gaging edge q' , which is destined to receive the rear or advancing edge of the sheet to be punched. The gage-bar may be set forward or backward by

20 means of adjusting screws Q' Q', which turn in threaded sockets carried by the saddles P P. After adjustment the gage-bar is preferably clamped firmly in place by set screws $r' r'$. The gage-bar near each end has fastened to it a supporting plate R or R', these plates being in the same plane as the plate e of the feed table. The function of these plates is to receive the advancing portion of the sheet when it is fed from row to row.

25 30 On one of these plates is carried a pair of preliminary gages S S, shown best in Fig. 4. These are mounted each on an arm s, the two arms s s being fastened on the opposite ends of a rock shaft s' from which projects an arm s^2 to which, as shown in Fig. 4, is jointed a rod t which extends to the front of the table B and terminates in a knob t', conveniently located to be grasped by the operator. By pushing this knob rearwardly the

35 40 rock shaft is oscillated so as to drop the gages S S down upon the plate R in operative position; by pulling the knob forward the gages are raised, as shown in Fig. 4, so that they are rendered inoperative and the sheet may be passed beneath them. To retain these parts in either position a yielding catch is provided which may conveniently be of the construction shown in Fig. 8 where the rod t is formed with two notches or

45 50 grooves, either of which may be engaged by a spring-pressed ball t^2 , the spring having sufficient stress to hold the rod with sufficient firmness in either position and yet permit it to be displaced to the other position by a suitably energetic pushing or pulling movement.

The feeding operation may now be understood.

55 Before inserting a new sheet the initial gages S S are dropped into operative position by pushing back the knob t'. The feed table C being moved to the right, as shown in Fig. 2, the sheet to be punched is inserted under the handle H, its right and left edges fitting snugly but freely between the end

frames f f. The operator turns the handle H so as to release the clamps G G and pushes the sheet forward until its advancing edge strikes the gages S S, being stopped thereby in the correct position for making the first 70 row of punchings. One corner of the sheet is then directly over the die D for the first punch. The operator then turns the handle H to cause the clamps G G to engage and hold the sheet. The gages S S, having thus 75 performed their function of initially locating the sheet, should now be lifted by pulling forward the knob t'. The operator then, by the usual foot treadles, starts the press, and when the punch, after the first punching operation, lifts and frees the sheet, the stop K moves down to the position shown in Fig. 3. The operator then, having his hand on the handle H, moves the feed table to the left, and before this movement is completed 80 the stop K moves back so that its teeth k intercept the rack teeth and stop the manual feeding movement. The operator, keeping his hand on the handle H, holds the feed table with its rack teeth snugly against the 85 stop K while the punch descends and cuts out the second punching. As the punch rises another feed movement is performed, and so on, until the punchings of the first 90 row have all been cut out. When this occurs 95 the right hand stop N abuts against the stop K so that even if the operator were inattentive no further feeding movement could be performed. The operator then releases the 100 treadle and stops the press in order to advance the sheet for the second row of punchings. He then turns the handle H to release the clamps G G and advances the sheet by pushing it forwardly until its advancing edge encounters the shoulder q' of the gage 105 Q, whereupon he reengages the clamps G G. The parts are now ready for cutting the second row of punchings. To start this the operator pushes the handle-bar H toward the right so that the half feed previously 110 described is performed, thereby bringing the position for the first punching of the second row to a point between the two last punchings in the first row. He then starts the machine and the sheet is alternately punched 115 and fed while traversing the second row. Fig. 6 shows the condition when the second row has been partly punched. During the punching of the first row the scrap cutters or shears F F will cut off a narrow strip 120 from the margin which is provided on the sheet, thus forming a true gaging edge for the sheet. During the cutting of the second row of punching these cutters act to shear off the superfluous scrap to the rear of the 125 second row of punchings (in a manner well understood), so that they shear a new advancing or gaging edge for the sheet, which at the next forward feed of the sheet will serve, by coming against the gage-bar shoul- 130

der q , to correctly gage the sheet for the third row of punchings. Thus the operation proceeds, the operator keeping one or both hands upon the handle H in order to move 5 the feed table, oscillating this handle at the end of each row of punchings to release and feed forward the sheet, and starting or stopping the press by means of the usual foot treadle. When the sheet is finally cut up 10 for making the last row of punchings, the remaining scrap is pushed off, the starting gages $S S$ are dropped into place against and a new sheet is inserted against these gages as before.

15 It will be understood that the gages $S S$ are adjustable on their arms $s s$ in order that their distance from the gage shoulder q' may properly accord with the spacing between the first and second rows of punchings. For each different size of punching 20 to be made an adjustment of the gage-bar Q and the gages $S S$ is required, and a new rack bar J and stop teeth k are required.

It is sometimes required to lower the stop 25 K when the press is stopped in order to move the feed table C to either side. For this purpose a handle T is provided which may be made, as shown, in one piece with the arm p' so that by manipulating this 30 handle the operator may press down the slide K' against the stress of its spring k' .

The manipulation of the machine thus described is quickly and easily learned. In the hands of an operator of any ordinary 35 skill and attention it may easily attain a speed approaching closely to that of the punching presses having a purely automatic feed. At the same time the machine is much less complicated, less liable to derangement, 40 and its initial cost and expense of maintenance are much less.

The invention is not limited to the precise 45 details of construction herein set forth, being susceptible of considerable variation in non-essential respects without departing from its essential features.

I claim as my invention:—

1. The combination with a punching press 50 of a laterally movable feed table having adjustable end frames, sheet-gripping clamps carried by said end frames, and an operating handle for simultaneously operating said clamps.

2. The combination with a punching press 55 of a laterally movable feed table, adapted to carry a sheet and permit the latter to be fed forwardly over it, sheet-clamping levers pivoted to said table, springs pressing said levers to engage the sheet, and an operating handle movable to release said levers.

3. The combination with a punching press 60 of a laterally movable feed table having a rack bar and a movable stop coacting with said rack bar to limit the feeding move-

ments of the table, the combined widths of 65 the abutting stop teeth being equal to half a feeding movement, whereby reversing the direction of feed insures a stagger feed.

4. The combination with a punching press 70 of a laterally movable feed table having a longitudinal undercut groove, a rack bar having clamping means entering said groove whereby to fasten the rack bar adjustably to the feed table, and a movable stop adjustable in said groove coacting with the 75 teeth of said rack bar to limit the feeding movements of the table.

5. The combination with a punching press 80 having a laterally extended bed, of a feed table laterally movable thereon, sheet-clamping means on said feed table, and an adjustable gage-bar applied to said bed for gaging the advancing movements of the sheet.

6. The combination with a punching press 85 having a punch and scrap cutter, of a feed table having solely a lateral movement, clamping means on said table for gripping a sheet to be punched, preliminary gages for locating the initial position of the sheet 90 on said table, and a stationary gage related to said scrap cutter for limiting the forward feed of the sheet relatively to the table to the correct distance between lateral rows of punchings.

7. The combination with a punching press 95 having a laterally extended bed, of a feed table laterally movable thereon, adapted to carry a sheet and permit it to be fed forward thereon, sheet-clamping means on said 100 feed table, preliminary gages for locating the initial position of the sheet on said table, a rock shaft having arms on which said gages are adjustably mounted, and an operating handle connected to said rock shaft for 105 displacing or replacing said gages.

8. The combination with a punching press 110 having a laterally extended bed, of a feed table laterally movable thereon, sheet-clamping means on said feed table, preliminary 115 gages for locating the initial position of the sheet, a rock shaft having arms on which said gages are adjustably mounted, an operating rod connected to said shaft whereby to displace or replace said gages, and a yielding retainer engaging said rod in either position for holding it until displaced therefrom.

9. The combination with a punching press 120 of a laterally extended bed therefor having a guiding rib projecting therefrom, of a movable feed table having solely a lateral movement, rollers on said table for rolling against the surface of said bed, and rollers perpendicular thereto rolling against the 125 face of said rib, whereby when the press is tilted back the weight of the feed table keeps said latter rollers engaged with said

rib to guide the movement of the feed table in a fixed, rectilinear path.

10. The combination with a punching press of a laterally movable feed table, a series of stop teeth carried thereby, and a movable stop in a stationary location co-acting with said stop teeth to limit the feeding movements of the table, said stop teeth and movable stop adapted to engage in either direction and relatively proportioned

to permit an initial half feeding movement upon reversing the direction of feed.

In witness whereof, I have hereunto signed my name in the presence of two subscribing witnesses.

CHARLES R. GABRIEL.
